UNITED STATES PATENT OFFICE

SIMON W. FARBER, OF BROOKLYN, NEW YORK, ASSIGNOR TO S. W. FARBER, INC.,
OF BROOKLYN, NEW YORK, A CORPORATION OF NEW YORK

DESIGN FOR A DISH

Application filed October 21, 1929. Serial No. 33,129. Term of patent 14 years.

To all whom it may concern:

Be it known that I, SIMON W. FARBER, a citizen of the United States of America, residing at Brooklyn, in the county of Kings, city and State of New York, have invented a new, original, and ornamental Design for Dish, of which the following is a specification, reference being had to the accompanying drawing, forming a part thereof.

In the drawing, Fig. 1 is a top perspective view of the dish, showing my new design, and Fig. 2 is a bottom perspective view thereof.

I claim:

The ornamental design for a dish substantially as shown.

SIMON W. FARBER.
